US00D855141S

(12) **United States Design Patent** (10) **Patent No.:** **US D855,141 S**
(45) **Date of Patent:** **** Jul. 30, 2019**

(54) **PROJECTILE**

(71) Applicant: **Count-on Tools, Inc.**, Gainesville, GA (US)

(72) Inventors: **Curtis Larry Couch**, Santa Rosa Beach, FL (US); **Jackson T. Strayhorn**, Cleveland, GA (US); **James C. Cash**, Gainesville, GA (US); **Alexis Z. Shook**, Alto, GA (US)

(73) Assignee: **COUNT-ON TOOLS, INC.**, Gainesville, GA (US)

(**) Term: **15 Years**

(21) Appl. No.: **29/623,574**

(22) Filed: **Oct. 25, 2017**

(51) LOC (11) Cl. **22-03**

(52) U.S. Cl.

USPC **D22/116**

(57) **CLAIM**

The ornamental design for a projectile, as shown and described.

DESCRIPTION

FIG. 1 is an exploded top perspective view of a projectile, showing our new design;

FIG. 2 is an exploded bottom perspective view thereof;

FIG. 3 is an exploded side elevation view thereof;

FIG. 4 is an exploded top plan view thereof;

FIG. 5 is an exploded bottom plan view thereof;

FIG. 6 is a top perspective view of the projectile, in the first stage;

FIG. 7 is a bottom perspective view thereof;

FIG. 8 is a side elevation view thereof;

FIG. 9 is a top plan view thereof;

FIG. 10 is a bottom plan view thereof;

FIG. 11 is a cross section view along the line 11-11;

FIG. 12 is a top perspective view of the projectile, in the second stage;

FIG. 13 is a side elevation view thereof; and,

FIG. 14 is a cross section view along the line 14-14.

1 Claim, 12 Drawing Sheets
